UNITED STATES PATENT OFFICE.

EUGENE WASHINGTON VEST, OF MULBERRY GROVE, ILLINOIS, ASSIGNOR TO MAJESTIC MFG. CO., OF ST. LOUIS, MISSOURI, A CORPORATION OF MISSOURI.

RANGE.

1,121,152.

Specification of Letters Patent. Patented Dec. 15, 1914.

Application filed July 15, 1912. Serial No. 709,598.

To all whom it may concern:

Be it known that I, EUGENE W. VEST, a citizen of the United States of America, and a resident of Mulberry Grove, in the county 5 of Bond and State of Illinois, have invented certain new and useful Improvements in Ranges, of which the following is a specification.

The present invention pertains to certain 10 provisions for preheating and distributing air in ranges or cooking stoves to promote combustion, and it consists in the novel features and combinations of parts as set forth in the following description and succinctly 15 defined in the annexed claims.

With reference to the accompanying 20 drawings wherein similar reference characters designate corresponding parts throughout the several views: Figure 1 is a vertical longitudinal section through a cooking range embodying the features of my invention. Fig. 2 is a horizontal section through the range with parts broken away. Fig. 3 is a fragmentary vertical section of the 25 range on line 3—3 of Fig. 1, with the grate bars removed. Fig. 4 is a perspective of the same with the top and front end wall removed and portions of the rear end and back side walls broken away. Fig. 5 is a 30 fragmentary vertical section on line 5—5 of Fig. 1, and Fig. 6 is a similar view on line 6—6 of Fig. 1.

My invention consists essentially in providing a range or cooking stove with air 35 conducting and delivering means of suitable design to direct air beneath the fuel zone for preheating and thence to the combustion zone.

In the present embodiment, the range 1 is 40 provided with an air conducting passage or draft flue 2 beneath the fire box, which communicates with air distributing units in the form of chambered lining sections 5, 6, 6^a and 7, 7 provided with narrow outlet openings 5', 6', 6'' and 7', 7' for directing air into the fire box over the grate 8.

The flue 2 is provided in my range by the installation within the range, beneath the fire box, of a U-shaped partition 20, which serves 50 to form an ash compartment, the sections of said partition being spaced from a side wall of the range, the bottom of the range and a side wall of the oven nearest the fire box, as will presently more fully appear.

55 The U-shaped partition 20 includes a bot-

tom section 21 above that portion of the bottom of the range which is located beneath the fire box; also side sections 22 and 23, and an end section 24, the latter extending upwardly from the bottom section 21, parallel with the rear wall of the range, and being provided with flanges 24' and 24'' which are secured, respectively, to a side wall of the range and the side wall of the oven. The side section 22 of the U-shaped 60 partition 20 extends upwardly from the bottom section 21 and forwardly from the end section 24 to the front wall of the range, this side section being provided at its upper end with an angular flange 22' which is secured to the adjacent side wall of the range over the air inlet controlled by the damper 65 9 and serves to hold said section parallel with and spaced from said side wall. The side section 23 of the U-shaped partition 20 70 includes an angular flange 23', similar to the flange 22' of the section 22, which is secured to the side wall of the oven nearest the fire box. The side section 23 is also provided with an angular vertical extension 75 23' which is secured to the side wall of the oven, and, in combination with the adjacent walls, serves to form a vertical flue 2'.

The header 3 of my range is a substantially 80 L-shaped hollow body comprising a stem 85 having a neck 31 extending into the flue 2' and a short transverse arm, and is supported by brackets 10 and 11 secured respectively to the side wall adjacent the fire box and the opposing side wall of the oven, 90 the header being preferably provided with a transverse bar 3' which rests upon a bracket 12 secured to said side wall of the range.

The transverse arm of the header 3, which 95 extends across the fire box, is located between the rear wall of the range, at the rear end of the fire box, and the end section 24 of the U-shaped partition 20. This arm is provided with a longitudinal opening 100 30 which communicates with the flue 2. The stem of the header 3 is provided with a downwardly extending neck which fits in the flue extension 2' and provides communication from said flue to the interior of 105 the stem of the header.

The lining section 6, 6^a and 7 are seated on the stem of the header 3 and have communication with the interior of this member in order that heated air may pass from 110

the stem of the header into said sections to escape therefrom through the narrow outlet openings 6', 6" and 7' to the fire box. The lining section 5 is seated on the trans-
5 verse arm of the header 3 and the heated air entering said arm from the flue 2 through the neck 5" in the opening 3" passes into said lining section to be dis-
charged through the narrow opening 5' into
10 the fire box.

25 and 26 are deflectors secured to the partition walls 22 and 23 by which ashes falling from the grate 8 are directed to the ash pan 27.

15 11' is the floor of the oven.

Having thus described my invention what I claim as new, and desire to secure by Letters Patent of the United States of America, is:—

- 20 1. A range having a bottom, a side wall provided with an air inlet opening, and an oven wall parallel with said side wall, a grate between said walls, a fire box lining adjacent to said grate, said fire box lining being provided with an air flue open at the bottom to receive air and open at the top to discharge air over said grate, a partition substantially U-shaped in cross section arranged below said grate to form an ash
25 compartment, said partition being arranged between said side wall and said oven wall, the said partition being separated from said walls and the bottom of the range to form a substantially U-shaped passageway through which air may be conducted from said air inlet opening to the flue in said fire box lining.
- 30 2. A range having a bottom, a side wall provided with an air inlet opening, and an oven wall parallel with said side wall, a grate between said oven wall and said side wall, a fire box lining adjacent to said grate, said fire box lining being provided with an air flue having a discharge opening
35 through which air may be discharged over
40
- 45

said grate, a partition substantially U-shaped in cross section arranged below said grate to form an ash compartment, the said partition being separated from said bottom as well as from said side wall and oven wall 50 to form a substantially U-shaped passageway, the said inlet opening being located at one end of said substantially U-shaped passageway and the said fire box lining being located at the other end thereof, so that the 55 air entering the stove at said inlet opening will flow downwardly along one side of said ash compartment then under the bottom of said ash compartment before passing to said fire box lining.

3. A range having a bottom, a front wall provided with an air inlet opening, and an oven wall parallel with said side wall, a grate between said oven wall and side wall, fire box lining members adjacent to a side 65 and end of said grate, said fire box lining members being provided with air flues having discharge openings through which air may be discharged over said grate, a partition arranged below said grate to form an 70 ash compartment, said partition being open at its front end to receive an ash pan and open at the top to receive the ash dropping from said grate, the bottom, side and rear walls of said partition being closed and separated from the adjacent walls to provide 75 passageways leading from said inlet opening to the air flues in the fire box lining members at the side and rear end of said grate, said passageways being formed 80 around the closed bottom and closed rear end of said partition and also between the closed side wall of said partition and the said oven wall.

Signed at Mulberry Grove Ill. this 13 85 day of July 1912.

EUGENE WASHINGTON VEST.
